UNITED STATES PATENT OFFICE.

ALBERT BROD, OF NEW YORK, N. Y.

DESIGN FOR A BROOCH OR SIMILAR ARTICLE.

Application filed June 24, 1927. Serial No. 22,545. Term of patent $3\frac{1}{2}$ years.

To all whom it may concern:

Be it known that I, ALBERT BROD, a citizen of the United States of America, residing at New York city, county and State of New York, have invented a new, original, and ornamental Design for a Brooch or Similar Article, of which the following is a specification, reference being had to the accompanying drawing, forming part hereof, in which the figure illustrates a perspective view of a brooch showing my new design.

I claim:

The ornamental design for a brooch or similar article, as shown.

Signed this 22nd day of June, 1927.

ALBERT BROD.
